UNITED STATES PATENT OFFICE.

FREDERICK E. GOLDSMITH, OF HAMILTON, OHIO, ASSIGNOR TO CERAMIC MACHINERY COMPANY, OF HAMILTON, OHIO, A CORPORATION OF OHIO.

TILE-COATING MACHINE.

1,238,128.

Specification of Letters Patent. Patented Aug. 28, 1917.

Application filed March 30, 1912. Serial No. 687,295.

To all whom it may concern:

Be it known that I, FREDERICK E. GOLDSMITH, a citizen of the United States, residing at Hamilton, county of Butler, and 5 State of Ohio, have invented certain new and useful Improvements in Tile-Coating Machines, of which the following is a specification.

My invention relates to machinery for 10 applying vitreous coating to tiles and similar objects. More particularly it relates to a machine for applying a very heavy coating. Further, it relates to means for first applying a moist or adhesive coating to the tiles 15 and then applying dry pulverized coating material to the moist or adhesive surface. Further, the invention provides means for primarily coating or dusting the tiles and then secondarily coating or dusting them, 20 and handling them between the two dusting operations in a proper manner so that the first application will not be destroyed or damaged.

I will now describe an exemplifying machine embodying my invention, as shown in 25 the accompanying drawing, in which the various elements are shown for the sake of clearness in a simple, diagrammatic form.

Figure 1 is an elevation of a representative embodiment of the invention.

Fig. 2 is a vertical longitudinal section of 30 one of the moisteners and dusters with intermediate conveyer.

Fig. 3 is a transverse vertical section 35 through one of the dusters, the word transverse being used with reference to the machine as a whole.

Referring first to Fig. 1, reference character A designates a primary moistening device; B a primary coating or dusting device; C a secondary moistening device, and D a secondary dusting device. a is a feed belt for supplying tiles or similar objects to moistener A; b is a belt for handling the 45 objects between moistener A and duster B; c is a belt between duster B and moistener C, and d is a belt between moistener C and duster D. Any suitable belt may also be provided to take away objects from the 50 duster D in an obvious manner.

1 designates an air pump driven by any convenient motor 2. The pump stores air under pressure in tank 3, from which air is

supplied to atomizers in moisteners A and C by pipes 4 and suitable valves 5.

55 Tiles are carried by feed belt a to the moistener A, where their upper faces are coated with size or other suitable moist or adhesive substance; the tiles are then carried by belt b to duster B, where pulverized 60 vitreous coating material is dusted upon the soft or adhesive surfaces of the tiles. The belt b may be of such length that suitable opportunity is given for partly drying the moistened surfaces of the tile in their 65 passage from the moistener to the duster when that is necessary. Belt c then takes the tiles from duster B in cases where an additional coating must be placed upon the tiles; additional size is applied in moistener 70 C; the tiles are carried forward by belt d and additional coating is dusted upon them in duster D; the tiles are then removed in any convenient way for firing.

75 Fig. 2 is an enlarged longitudinal section through one of the moisteners A and duster B. The moistener consists of a housing or box 10 within which is an atomizer or sprayer 11. This comprises a trough 12 in which is swiveled a fluid nozzle 13. Within 80 the fluid nozzle is fixed an air nozzle 14 carried on the end of pipe 15, which is swiveled in the air pipe 4 at 16. This swiveling provides means by which the spray nozzle, consisting of the fluid nozzle 13 and air nozzle 85 14, may be rotated so that the atomizer points downward at the tiles or upward into the dome-shaped top of the box, as may be desired. The particular form of atomizer described is only representative and any suitable device for the purpose may be employed.

90 Below the box 10 is a combined reservoir and pump 20 consisting of a tub mounted on a rotor 21 suitably impelled. The bottom of box 10 is tapered off as at 17, to discharge into the tub. Within the tub is a pipe 22 terminating at 23 at the bottom of the tub in a tangential portion, the opening of which is directed against the direction of 95 motion of the tub. When the tub is suitably supplied with fluid, such as size, and rotated at proper speed, the centrifugal effect and momentum of the fluid forces it up to the tangential opening 23 and pipe 22, 100 105 from which it is discharged at 24 into the

trough 12. The pipe 12^a is to maintain level of fluid in trough 12 and return excess fluid to reservoir 20. Any excess continually flows from the ends of the trough to the bottom of the box and back to the tub.

In the back and front walls of the box 10 there are openings 30 of sufficient height to pass the tile or other object to be coated. Within the box is a series of transverse rollers 31 and there are one or more rollers 32 outside the box adjacent to the openings 30. These rollers are all rotated in the feeding direction by suitable gearing, details of which are not important.

Above the openings 30 within the box, are drip-troughs 33, which prevent size from running down across the openings 30.

Tiles delivered by the feed belt *a* of Fig. 1, are passed through box 10 by rollers 31. Size is sprayed directly upon the tiles by the atomizer when it is directed downward as shown in Fig. 2, or else the entire interior of the box may be filled with mist of suitable density, and this is applied to the tiles in their passage without direct air blast. Superfluous size gathering upon the walls of the box runs down and is returned to the tub for repumping. Passing from the moistener A, tiles are carried by the belt *b* to the first duster B, which will now be described.

The front and back walls of the dust box B are provided with openings 40 for the passage of the tile, and within the box are rollers 41 similar to those already described with reference to the moistener. At one end of the box is a bin 42 with a hinged cover, in which the pulverized coating material is placed. This discharges through the opening 43 at the bottom of partition 44 and is taken up by blades or scrapers 45 carried by scraper belt 46. This belt passes over drums or pulleys 47 at the ends of the box and is impelled by any suitable kind of driving connection. The partition 44 is curved so that material taken up by the blades is confined between the partition and the belt as the right-hand blades rise around their pulley. The belt is provided with perforations 48 or with a central space throughout its length. As the belt passes away from the partition, the powder is prevented from falling by a shelf 49. Above the rollers is a screen 49. Another shelf 50 at the other side of the screen may be provided to protect the bearings of the rollers. The powder carried by the belt blades is sifted through screen 49 and deposited upon the tiles to which it adheres thickly because of the moisture or size previously applied. The screen equalizes the

deposit of coating over the entire face of the tiles. Superfluous coating deposited in any part of the box is scraped back toward the right-hand end and used over again.

Moistener C may be a substantial duplicate of moistener A. But the tiles which come to moistener C have upon them a deposit of dust received in box B, and to avoid blowing away any of this dust, the atomizer in box C is usually directed upward, as shown, and moistener in box C is thus deposited by the indirect method without direct blast of air upon the tiles. Duster D may be substantially a duplicate of duster B.

This coating apparatus is designed largely to apply a very heavy coating to the tiles and it is sometimes impossible to make this coating sufficiently heavy with a single treatment even by the sizing and dusting method. This is why a second moistener and duster are usually provided, as shown in Fig. 1. Also, to give the pulverized material sufficient time to properly adhere to the tile after the first application. Belt *c* may be made of considerable length and in some cases a heater may be supplied so that the primary heavy coating of dust will properly set before the second application of moisture and dust is made. Belt *c* as shown in Fig. 1 is broken in the middle to indicate that it may be of any considerable length to allow of this setting of the primary coating.

A great many different forms of mechanism for carrying out this process have been devised, and the foregoing is only one exemplification, and I do not limit myself in any respect to details.

Reference is made to applicant's co-pending application, Serial No. 689,825, for a process of coating tiles and the like.

100

I claim:

In coating apparatus, the combination of a first moistening box, a first dusting box, a second moistening box, liquid spraying means therein, means for directing said spraying means upward to provide an atomized spray directed away from the tiles, upon which said spray falls without disturbing coating previously deposited, a second dusting box, and conveying means for passing tiles or the like through said boxes in the order named, said means being constructed and arranged to permit the coated surface of the tiles to dry somewhat between the first dusting box and the second moistening box.

FREDERICK E. GOLDSMITH.
